UNITED STATES PATENT OFFICE.

MATTHIAS JOSLYN RICE, OF BOSTON, MASSACHUSETTS.

DESIGN FOR A PHOTOGRAPHIC-CARD FRAME.

Specification forming part of Letters Patent No. 5,050, dated June 27, 1871.

To all whom it may concern:

Be it known that I, MATTHIAS JOSLYN RICE, of Boston, in the county of Suffolk and State of Massachusetts, have invented and produced a new and original Design for Card-Photograph Frames, of which the following is a specification:

Four flat pieces or bands, of wood, preferably, grooved longitudinally, so as to leave five beads—the two outer ones the largest—are placed together so as to leave in the center of them an oblong space, the two longer pieces crossing and being fastened to the shorter pieces in a channel cut across in which they are sunk, and the light ends projecting an inch or thereabout. On the upper side of this frame, at each corner, respectively, is placed diagonally and fastened a flat piece of wood, grooved with four longitudinal grooves, thus leaving five beads—the two outer

ones the largest on the upper surface—parallel to and at a distance of three-eighths of an inch (more or less) from the four first-named pieces of wood, which pieces pass from the projecting end of one of the first-named pieces to and beyond, respectively, the projecting end of the piece of the frame parallel to it. These narrow pieces are grooved into and fastened to the pieces over which they pass, and are of inferior length to the pieces of the frame to which they run parallel.

I claim as my invention—

The design for a card-photograph frame, as shown and described.

MATTHIAS JOSLYN RICE.
